Primary Examiner — Thomas Johannes*Assistant Examiner* — Shawn T Gingrich(74) *Attorney, Agent, or Firm* — Drinker Biddle & Reath LLP(57) **CLAIM**

The ornamental design for an electrical connector, as shown and described.

DESCRIPTION

FIG. 1 is an exploded perspective view depicting the new design of an electrical connector;

FIG. 2 is a perspective view thereof;

FIG. 3 is right side view thereof, and the left side view is a mirror image thereof;

FIG. 4 is a front view thereof, and the back view is a mirror image thereof, and;

FIG. 5 is a top view thereof, and the bottom view is a mirror image thereof.

The broken line in the figure drawings is included to show portions of the article that form no part of the claimed design.
